UNITED STATES PATENT OFFICE.

HEINRICH MACHTANZ, OF HANAU, PRUSSIA, GERMANY.

CIGAR-HOLDER.

SPECIFICATION forming part of Letters Patent No. 404,644, dated June 4, 1889.

Application filed March 23, 1888. Serial No. 268,313. (Model.) Patented in England December 19, 1887, No. 17,443, and in Germany January 6, 1888, No. 42,918.

To all whom it may concern.

Be it known that I, HEINRICH MACHTANZ, manufacturer, of Hanau, in the Kingdom of Prussia and German Empire, have invented 5 a new and useful Improved Cigar-Holder, of which the following is a specification, reference being had therein to the accompanying drawings, no patents being obtained by me anywhere for this invention, save in Germany, 10 No. 42,918, dated January 6, 1888, and Great Britain, No. 17,443, dated December 19, 1887.

This invention relates to a small cigar-holder for holding and smoking cigars of any size and thickness, which holder is not thicker than a 15 lead-pencil.

In the accompanying drawings, Figure 1 is a view in elevation of the holder. Fig. 2 is a side view of the same with the cap screwed up. Figs. 3 to 6 show details of the new cigar-holder. Fig. 3 is a view showing the cap *c* 20 screwed down. Fig. 4 shows a view taken rectangularly to Fig. 3, cap *d* being shown in section. Fig. 5 is a longitudinal section. Fig. 6 is a horizontal section on line *x x*, Fig. 5.

25 The new cigar-holder is of small dimensions. It occupies very little space, and can therefore be very comfortably put in the waist-coat or other pocket, while being an economy to every smoker of cigars, because the cigars 30 can be smoked down to the very end.

The holder consists of a tube *a*, which at its one end is connected with the pipe-tip *a'* and at its other end is provided with a metal box *b*. The box *b* is provided with a screw-thread 35 *g*, over which slides the cap *d*, which cap is provided with a nut screw-thread. The screw-thread of the box *b* is entirely covered by that of the cap *d*. From the metal box the tube *c* projects, the outer end of which is formed as 40 a knife and is provided with an opening *c'*,

communicating with the bore of tube *a* and of the pipe-tip *a'*.

The box *b* on the end of the tube *a* is stationary, and the cap *d* is adapted to have a spiral movement on said box by reason of an indentation in its surface corresponding to the threads in the box *b* and in which it fits. By holding the tube *a* in one hand and turning the cap *d* the said cap will be advanced spirally from the position shown in Fig. 1 to 45 cover the point of the holder, as in Fig. 2. When in use, the cap *d* is back in the position shown in Fig. 1, and the sharpened end of the holder is forced into the cigar until the opening *c'* is covered, and then the smoke passes 50 55 through the opening *c'* and the tube *a* to the mouth. When not in use, the cap *d* is advanced, as described, to cover the point, and the holder may thus be carried in the pocket without injury thereto.

60 What I claim, and desire to secure by Letters Patent of the United States, is—

1. A cigar-holder consisting of a smoke-tube, a holding-point on said tube provided with an opening leading to the interior of the tube, and a movable cap for covering said point when the holder is not in use, substantially as 65 described.

2. A cigar-holder consisting of a smoke-tube, a holding-point, a box on said tube having 70 threads on its periphery, and a covering-cap surrounding said box and in engagement with the threads thereof, substantially as described.

In witness whereof I have hereunto set my hand in presence of two witnesses.

HEINRICH MACHTANZ.
